UNITED STATES PATENT OFFICE.

JOHN MANNING VAN HEUSEN, OF BOSTON, MASSACHUSETTS.

GARTER.

1,357,929.

Specification of Letters Patent.

Patented Nov. 2, 1920.

Application filed May 28, 1920. Serial No. 384,874.

To all whom it may concern:

Be it known that I, JOHN MANNING VAN HEUSEN, residing at Boston, in the county of Suffolk, State of Massachusetts, have invented certain new and useful Improvements in Garters; and I do hereby declare the following to be a full, clear, and exact description of the invention, such as will enable others skilled in the art to which it appertains to make and use the same.

An inherent difficulty present in many types of garters at present in use, wherein the garter depends, for its permanency of position, upon the pressure which it exerts upon the leg, is that to a greater or less extent this pressure tends to restrict the free circulation of the blood, often resulting in discomfort and annoyance and, in some instances, in positive injury to the wearer.

The main purpose of the present invention is to provide a garter which will resist any tendency to work downwardly and which, in its preferred form, will even tend to work upwardly on the leg, so that the permanency of position of the garter will not depend upon the usual restrictive pressure of the customary kind.

In the practice of the invention, the object proposed is attained by the use of a fabric, such as velvet or velveteen or the like, wherein the pile or filaments of the fabric, when in contact with the bare leg or drawers leg of the wearer will resist downward travel. In fact, as hereinbefore indicated, a garter made of or provided with pile fabric so arranged that when the garter encircles the leg the pile filaments will be directed downwardly, has an actual tendency to travel upwardly. The resultant effect is that not only is it feasible to obtain a sufficiently effective frictional grip between the garter and the leg without the necessity of drawing the garter at all tightly about the leg, but the garter likewise has a constant tendency to keep the hose, or half hose, as the case may be, unwrinkled.

In some instances, the velvet, velveteen, or other appropriate pile fabric may constitute the entire main body portion of the garter, or it may have elastic threads or elastic cords or elastic fabric sections associated therewith, so as to impart some minor degree of elasticity to the garter as a whole should that be desired. Moreover, as will hereinafter appear, the pile fabric may be more or less permanently attached to the

hose or half hose, or it may constitute an entirely separate garter.

Referring now to the accompanying drawing illustrating several embodiments of my invention;

Figure 1 is a view showing one form of the improved garter as attached to the upper inner edge of a sock or stocking;

Fig. 2 shows a modification as applied to a common type of garter worn by men;

Fig. 3 shows another modification in which elastic portions are combined with the garter;

Fig. 4 shows a further modification as applied to a well-known type of garter;

Fig. 5 shows a still further modification in which the garter is provided with pile fabric on both sides;

Fig. 6 is an enlarged section on the line 6—6 of Fig. 4;

Fig. 7 is a sectional view on a much enlarged scale, through a known kind of velvet, in which the pile of the velvet is at an acute angle to the body portion thereof.

Referring now to Fig. 1, 1 indicates a sock or stocking, to the inner upper edge of which the garter 2, provided with the velvet, velveteen or like pile fabric surface 3, is attached. The pile of the fabric is shown at 4 and it will be noted that it inclines downwardly and inwardly. The numerous small filaments or threads of the pile fabric engaging the leg or drawers leg of the wearer at an acute angle provide frictional contact between the garter and the leg sufficient to obviate any necessity of drawing the garter otherwise than snugly (but not too tightly) around the leg in order that it may perform its function. Consequently, the important advantage is obtained that there is no constriction of circulation in the leg of the wearer in the use of the garter.

It has been found by actual test that with a garter made of pile fabric, the expansion and contraction of the muscles of the leg encircled by the garter react in such manner as to exert an actual tendency for the garter to work upwardly. It should, of course, be understood, that this tendency, arising from the action of the many short threads forming the pile fabric, is not so marked or so strong that it will impose an excessive upward pull on the hosiery or one that would become uncomfortable. It is, however, strong enough to effectively hold up the sock or stocking.

Fig. 2, shows a man's garter, provided with the usual sock-engaging device 6, and a catch 7. The inside of the garter 5 is faced with velvet, velveteen, or like pile fabric engaging the bare leg or the drawers leg α of the wearer; or the garter may be made up wholly of pile fabric, with the pile on the inside. The portions 8 of the garter to which the supporting piece 9 is attached, 10 may be made elastic, if desired.

Referring to the modification shown in Fig. 3, the garter there shown consists of a number of sections 10 which are either made of or faced on the inside with velvet, velveteen or other pile fabric, the pile of which inclines downwardly and inwardly with respect to the wearer's leg. In this case the pile is indicated at 10'. This garter also comprises one or more elastic inserts 8' suitably arranged so as to impart moderate elasticity to the garter as a whole.

The garter shown in Fig. 4 consists of a body portion 11 which, as indicated in Fig. 6, comprises a piece of velvet, velveteen or like pile fabric 12, the pile 13 of which is on the inside. A piece of silk or satin or the like 14 may be used to give an outer appearance of high quality and finish. The sock holder 6 is supported by the cords 15, 20 which engage with suspending buttons 16, and which may be elastic if desired.

Referring to Fig. 5, a modification is shown in which the garter is provided both on the inside and the outside with the velvet, 35 velveteen or other pile fabric, the pile of which, on both sides, inclines downwardly. The body of the garter is indicated at 17 while the pile that inclines downwardly and inwardly is indicated at 18 and the pile that 40 inclines downwardly and outwardly is indicated at 19. 20 indicates the trouser leg of the wearer. The inner pile fabric 18 subserves the same functions as the inner pile fabric in the other types. The outer pile 45 fabric 19 is adapted to engage with the inner side of the trousers leg of the wearer in such manner that, due to the ordinary relative movement and periodic contact between the trouser leg and the garter in ordinary 50 use, there is a tendency for the garter to engage with and be moved upwardly by the trouser leg. The fact that the pile fabric 12 inclines downwardly and outwardly provides such an engagement between the pile 55 fabric and the trouser leg. While, of course,

the trouser leg is not always in contact with the garter, it is quite customary for men, when sitting down to pull up the trousers somewhat, whereby the garter would also tend to be correspondingly raised; whereas, 60 when the trouser leg moves downwardly, there is no engagement between the downwardly inclined pile and the trouser leg and consequently no tendency to move the garter downward.

Referring to Fig. 7, which is a diagrammatic section, on a much enlarged scale, of a known weave of velvet, the warp and woof threads forming the body of the velvet material are indicated at 21 and 22. Interlaced with these threads are a plurality of pile-forming threads 23, which spread out into the pile filaments 24, which incline downwardly at an acute angle to the body of the fabric.

While several embodiments of the invention are illustrated, it will be understood that it may be carried out in other ways than those illustrated. The main characteristic feature of the invention is providing a garter of the band-type with a suitable pile facing giving a sufficient degree of frictional contact between the garter and the leg of the wearer, the nature of the frictional contact being such that the garter in 85 normal use, tends to work upwardly, while at the same time, offering a marked resistance to downward movement.

I claim:

1. A band garter, provided on its inner 90 surface with pile fabric presenting contact filaments downwardly and inwardly inclined to the leg or drawers leg of the wearer.

2. A band garter, provided on its outer 95 surface with pile fabric presenting contact filaments downwardly and outwardly inclined to the trousers leg of the wearer.

3. A band garter provided on its inner 100 surface with pile fabric presenting contact filaments downwardly and inwardly inclined to the leg or drawers leg of the wearer and presenting contact filaments downwardly and outwardly inclined to the trousers leg of the wearer.

4. A band garter of the construction defined in claim 1 and provided further with elastic elements forming a part of the band.

In testimony whereof I affix my signature.

JOHN MANNING VAN HEUSEN.
